UNITED STATES PATENT OFFICE.

GEORGE BREWER GRIFFIN, OF EDGEWOOD PARK, PENNSYLVANIA, ASSIGNOR TO
WESTINGHOUSE ELECTRIC AND MANUFACTURING COMPANY, A CORPORATION
OF PENNSYLVANIA.

HUMIDIFIER AND AIR-CLEANER.

1,130,267.

Specification of Letters Patent.

Patented Mar. 2, 1915.

Application filed July 11, 1911. Serial No. 637,999.

To all whom it may concern:

Be it known that I, GEORGE B. GRIFFIN, a citizen of the United States, and a resident of Edgewood Park, in the county of Allegheny and State of Pennsylvania, have invented a new and useful Improvement in Humidifiers and Air-Cleaners, of which the following is a specification.

My invention relates to means for promoting the circulation of air and, at the same time, moistening and cleaning the air the circulation of which is set up and promoted by the device.

The object of my invention is to provide a means which may be readily and cheaply applied to a fan and which will be effective in cleaning and moistening the air which is set in motion by the fan blades.

My invention is illustrated in the accompanying drawings, in which—

Figure 1 is a view, mainly in side elevation but partially in section, of a fan motor equipped with my invention, Fig. 2 is a view, partially in section and partially in elevation, of the air-moistening and cleaning attachment shown in Fig. 1, and Fig. 3 is a sectional detail view of a fabric-fas-

tening device.

My invention is shown as applied to what is known as a desk fan driven by an electric motor, but it will be understood that the air-moistening and cleaning device may be utilized in connection with any fan, however the same may be driven, and in connection with any means for producing a current of air, whatever may be its location or relation to other apparatus.

Referring now specifically to what is shown in the drawings, the electric motor 1 may be of any well known or desired type for driving fan blades, the fan blades 2 being rigidly mounted upon the shaft 3 of the motor and their hub 4 being provided with a groove 5 to receive a belt 6.

Mounted loosely upon the outer end of the shaft 3, is a wheel 7, the inner ends of the spokes 8 of which are clamped between two disks 9 and 10, the former of which is integral with the hub 11 and the latter of which is fastened in position by screws 12 and a nut 13. The outer ends of the spokes 8 are seated in rim segments 14 that may be fastened together by any desired or suitable means, dowel pins 15 being indicated as centering devices and pivoted latches 16

and coöperating pins 17 being indicated for holding the abutting ends of the segments in engagement. The rim segments are provided with sets of spring pins or clips 18 and the spokes 8 are provided with similar device 19, these pins or clips being provided as supports for sheets of textile fabric 20, each sheet being cut to substantially the form of the space between the rim and adjacent spokes and being fastened in position by hooking the edges over the projecting ends of the spring clips or pins. The wheel, when thus covered, presents a substantially continuous disk of fabric to the current of air delivered by the fan. The fabric may be of any suitable character that is of sufficiently open mesh to permit the fan blades to blow air through it. Instead of providing a series of sections of fabric, as here indicated, it will, of course, be possible to employ a single sheet of fabric of the proper form or any number of sheets other than what I have indicated in the drawing. In order to moisten the fabric for the purpose of cleaning and moistening the air that is blown through it by the fan, I mount a trough 21 upon a suitable base 22 and fill this trough with liquid, preferably water, which may be scented, if desired, to such a height that a portion of each sheet of fabric will dip into the water as the wheel is rotated. Capillary attraction will serve to distribute the water or other liquid over the entire fabric, so that any air blown through the wheel will be cleaned and moistened.

In order to drive the wheel at a slow speed, I mount a friction pinion 23 upon a shaft 24 in position to engage the periphery of the rim of the wheel and mount the shaft in suitable bearings in a pivoted frame 25, between the arms of which and upon the shaft 24, I mount a pulley 26 to receive the belt 6 which is driven by the motor 1. The lower end of the frame 25, which carries the shaft 24, is mounted upon a rod 27 and the latter is mounted in bearings in a standard 28 with which the base 22 is provided. In order to force the friction pinion 23 into engagement with the rim of the wheel 7, I surround the rod 27 with a helical spring 29, the ends of which respectively engage the frame 25 and the standard 28, these devices merely being indicative of any suitable means for performing the desired functions.

It will be understood from the drawings

and the foregoing description that the fabric-covered wheel will be driven at a slow speed relative to the speed of the motor shaft and, consequently, that the fabric will be gradually dipped into the liquid in the trough 21 and thus keep moistened sufficiently to clean the air that is blown through the fabric by the fan blades and also wash out a large part of the accumulated dust as well as again moisten it to the desired degree. It will also be understood that the structural details and dimensions of the wheel and the means for driving it may be varied from what I have shown and described in any manner or degree within the scope of the appended claims.

I claim as my invention:

1. The combination with a fan motor and a fabric-covered wheel concentrically mounted with respect to the fan blades, of speed-reducing gearing between the motor shaft and said wheel and a liquid-containing trough in which successive portions of the outer edge of said fabric are submerged as the wheel is rotated.
2. The combination with an electric motor having fan blades mounted upon its shaft, of a wheel concentrically mounted with respect to said fan blades and provided with a circular fabric-cover, speed-reducing gearing between the motor and said wheel and a trough containing liquid in which the outer edge of the fabric dips as the wheel is rotated.
3. The combination with an electric motor having fan blades mounted upon its shaft, of a wheel having sheets of fabric mounted thereon to cover the spaces between its spokes, speed-reducing gearing between the motor and said wheel, and a trough containing liquid into which the outer edges of the sheets of fabric successively dip as the wheel is rotated.
4. The combination with an electric motor and fan blades mounted upon the motor shaft, of a concentrically mounted wheel in front of the fan blades and provided with detachable segments of fabric, speed-reduc-

ing gearing between the motor and said wheel, and a liquid-containing trough into which the outer edges of the fabric segments dip as the wheel is rotated.

5. The combination with a fan motor and a fabric covered wheel mounted in front of the fan blades, of speed-reducing gearing between the motor and said wheel, and a liquid-containing trough into which the outer edges of the fabric dips as the wheel is rotated.

6. The combination with a fan motor, of a wheel rotatably mounted in front of the fan blades and provided with a detachable fabric covering, speed-reducing gearing between the fan motor shaft and said outer edge of the wheel, and a liquid-containing trough into which the wheel fabric dips as the wheel is rotated.

7. The combination with a fan and driving means therefor, of a fabric-covered wheel mounted in front of said fan, speed-reducing gearing between the fan-driving means and said wheel, and a liquid-containing trough into which the outer edge of the wheel fabric dips as the wheel is rotated.

8. The combination with a fan and a fabric-covered wheel rotatably mounted in front of said fan, of means for driving said wheel at a relatively slow speed, and a liquid-containing trough into which the outer edge of the fabric dips as the wheel is rotated.

9. The combination with a motor-driven fan and a fabric-covered disk rotatably mounted in front of said fan, of speed-reducing gearing between the fan shaft and the disk, and a liquid-containing trough into which the outer edge of the fabric dips as the disk is rotated.

In testimony whereof, I have hereunto subscribed my name this 17th day of June, 1911.

GEORGE BREWER GRIFFIN.

B. B. HINES.

It is hereby certified that in Letters Patent No. 1,130,267, granted March 2, 1915, upon the application of George Brewer Griffin, of Edgewood Park, Pennsylvania, for an improvement in "Humidifiers and Air-Cleaners," errors appear in the printed specification requiring correction as follows: Page 5, lines 64-65, strike out the words "outer edge of the"; same page, line 66, before the word "wheel" insert the words *outer edge of the*; and that the said Letters Patent should be read with these corrections therein that the same may conform to the record of the case in the Patent Office.

Signed and sealed this 23d day of March, A. D., 1915.

[SEAL.]

J. T. NEWTON,

Acting Commissioner of Patents.
